Inventor:
John M. McCLOUD,
By his Attorney, Geo. T. Niath

Patented Apr. 24, 1923.

1,452,612

UNITED STATES PATENT OFFICE.

JOHN M. McCLOUD, OF BROOKLYN, NEW YORK.

MOUNT FOR VEHICLE CURTAIN WINDOWPANES.

Application filed June 2, 1921. Serial No. 474,333.

To all whom it may concern:

Be it known that I, JOHN M. McCLOUD, a citizen of the United States, and a resident of the borough of Brooklyn, county of 5 Kings, city and State of New York, have invented certain new and useful Improvements in Mounts for Vehicle Curtain Windowpanes, of which the following is a specification.

10 My improvements relate to novel means and method of mounting of elastic resilient panes of transparent material in the window spaces of vehicle curtains; and while applicable to vehicle curtains generally, are 15 especially designed for use in conjunction with the flexible curtains used on automobiles, where window pane replacement is frequently desirable or necessary.

20 The main object of my invention is the provision of a simple but effective encasement frame upon the curtain for the reception and support of the edges of a plate of transparent elastic resilient material in such manner that detachment and replacement 25 thereof may be expeditiously accomplished with ease and facility of manipulation, and without the necessity for the employment of skilled labor, or resort to a repair shop, thereby obviating delay and expense otherwise and heretofore incidental 30 to the substitution of a new for an old or broken window pane of the character designated.

35 To this end my invention consists in the specific combination, construction, and arrangement of parts and devices described and claimed, distinctive features being the provision of a tubular casing for the edge of the transparent elastic resilient pane, said casing being formed with an insert slot, and the use, in conjunction therewith, of a 40 gasket for retaining the edge of the transparent pane therein, said gasket being held in position by the tubular form of the casing, all as hereinafter fully set forth.

45 In the accompanying drawings,

Fig. 1, is an elevation of a portion of one side of a vehicle curtain provided with my improved window structure, of approximately square configuration;

50 Fig. 2, is a similar view, showing such a window of oval configuration;

Fig. 3, is an enlarged cross sectional perspective of the encasement frame;

55 Fig. 4, is a similar view showing the

adaptation of my device to a curtain provided with a lining;

Fig. 5, is a sectional detail illustrating a modification in the character of gasket used in the encasement frame;

60 Fig. 6, is a sectional perspective of a portion of the tubular encasement frame shown in the other figures of the drawings.

65 The window pane *p*, may consist of any transparent or translucent medium such as celluloid or analogous material adapted to the purpose of observation therethrough, or the admission of light, according to circumstances and requirements of use. My invention is designed particularly for use in 70 conjunction with the panes of flexible transparent material at present in vogue, such as a relatively thin sheet of celluloid having sufficient elasticity and resilience to adapt it to yield to a certain extent under pressure 75 while tending constantly to assume its normal flat shape.

75 *C*, represents a portion of a flexible curtain, formed of leather, rubberized or enamelled cloth, canvas, or, in fact, any appropriate pliable material. A suitable window opening is formed in the curtain, sufficient marginal edge *c*, being allowed to admit of overlap and insertion in my tubular case- 80 ment or frame *F*; and by the term "tubular" as used herein with relation to said encasement frame *F*, I mean to designate 85 any hollow tubulate structure adapted to function as a receptacle for the edge of the pane *p*, and of a retaining gasket *g*, for holding the said edge of the pane firmly in position,—said tubular encasement frame *F*, being formed with a continuous circum-

90 ambient insert slot *f*, on its inner side for the reception and accommodation of said edge of the pane *p*, and said gasket *g*. Such an encasement frame may be conveniently and cheaply constructed of metallic or other tubing, having the insert slot *f*, formed in one side thereof, said slot being of sufficient 95 width to admit of a suitable gasket *g*, which may consist of a rubber tube as indicated in Figs. 3 and 4, of the drawings, or of any suitable plastic material (as indicated in Fig. 5) inserted into the frame after the 100 introduction of the edge of the pane *p*.

Aluminum tubing, or hard rubber tubing, may be used to advantage in the formation of my tubular encasement frame where 105 lightness of weight is a desideratum; or 110

the frame F, may be constructed of sheet metal bent over into tubular form with the insert slot between the edges; as, in fact, I do not limit myself to any specific construction of tubular frame F, provided it is formed with the longitudinal insert slot f, on its inner side.

The marginal edge c, of the curtain C, is folded, inserted, and cemented to one inner side of the frame F, so as to afford a permanent connection between the parts; and when the curtain is lined, the edge l', of the lining l, is in like manner folded, inserted in, and attached to, the other inner side of the tubular frame, as shown in Fig. 4.

By my construction and arrangement of parts the replacement of the elastic resilient pane p, may be readily effected without even the necessity of removing the curtain from its support; and without the need of skilled labor,—thus obviating the resort to a repair shop for the purpose, and the delay and expense that would be thereby involved. Furthermore, by my method of mounting the pane p, all the component parts of the joint are enclosed and hidden from observation, and a neat symmetrical external appearance and finish is attained.

During the insertion or removal of the pane p, the elastic resiliency thereof admits of the edges of the pane being readily sprung into or out of engagement with the edges of the slot f, of the frame F.

What I claim as my invention and desire to secure by Letters Patent is,

1. In combination with a curtain of the character designated, a window mount there-

for, comprising a tubular encasement frame formed with an insert slot on the inner side thereof and attached to an inturned marginal edge of said curtain, an elastic resilient window pane the edge of which is positioned in said encasement frame, and a gasket inserted in said frame and bearing against the edge of the pane, for the purpose described.

2. In combination with a curtain of the character designated, a window mount therefor, comprising a tubular encasement frame formed with an insert slot on the inner side thereof and attached to an inturned marginal edge of said curtain, an elastic resilient window pane the edge of which is positioned in said encasement frame, and a rubber gasket inserted in said frame and bearing against the edge of the said pane, for the purpose described.

3. In combination with a curtain of the character designated, a window mount therefor, comprising a tubular encasement frame formed with an insert slot on the inner side thereof and attached to an inturned marginal edge of said curtain, and also attached to an inturned marginal edge of the lining of said curtain, an elastic resilient window pane the edge of which is positioned in said encasement frame, and a gasket inserted in said frame and bearing against the edge of the pane, for the purpose described.

JOHN M. McCLOUD.
